UNITED STATES PATENT OFFICE

2,031,457

FUSE

George R. Brown, Bridgeport, Conn., assignor to
General Electric Company, a corporation of
New York

Application February 27, 1934, Serial No. 713,081

3 Claims. (Cl. 200—130)

My invention relates to fuses and more particularly to fuses of the plug type. Plug fuses are generally used to protect the individual circuits of a house wiring system.

5 Operation of these fuses depends upon the melting of a fuse link to open the circuit. Fuses of low current rating operate quickly on heavy current overloads due to the rapid melting of the relatively small fuse link. On small overloads 10 which are slightly in excess of the rating of the fuse the arc drawn between the severed ends on the melting of the fuse link is unstable and so will not persist for a very long time. Difficulty has been experienced with fuses of high current 15 rating which may operate quite satisfactorily on relatively heavy overloads as on short circuits. These fuses may fail to operate on the long persistence of the arc on overloads that are slightly in excess of the rating of the fuse. The long 20 persistence of the arc or the failure of the fuse to operate may result in the arc destroying the fuse and then striking between parts of the fuse support. This may result in serious damage to the fuse support ultimately resulting in a fire 25 or may cause damage to the electrical apparatus connected in the circuit.

The object of my invention is to provide a fuse which will operate more certainly and quickly especially when provided with a fuse link having 30 a relatively high current rating.

What I consider to be novel and my invention will be better understood by reference to the following specification and appended claims when considered in connection with the accompanying 35 drawing, in which Fig. 1 is a side view of my improved fuse with a portion of the metal shell cut away to expose the part beneath; Fig. 2 is a sectional view along the line 2—2 of Fig. 1 looking in the direction indicated by the arrows, and 40 Fig. 3 is a sectional view along line 3—3 of Fig. 1 looking in the direction indicated by the arrows.

In the drawing the plug fuse of my invention is indicated generally by the numeral 10 and consists of a base 11 and a cap 12 both formed of 45 molded insulating material. Cap 12 is provided with a cylindrical extension 13 which overlies a considerable portion of the base 11. A center contact 14 is provided for the fuse and is secured in a central opening in the base 11. The second contact for the fuse consists of a screw shell 15 which threads on integral screw threads 16 provided on cap 12, as best indicated in Fig. 1. Screw shell 15 serves to secure base 11 and cap 12 together. Radial movement between cap 12 and 50 base 11 is prevented by the seating of projections 55

17 and 18 of base 11 in corresponding recesses provided in cap 12. A fuse link 19 is provided and connected at one end to center contact 14 and at the other end to screw shell 15. To permit examination of the condition of fuse link 19, a 5 transparent window 20 is secured over an opening provided in cap 12 and is held in position by engagement with the top of base 11. To permit the escape of gases generated on the operation of the fuse, a space is provided between the side 10 walls of base 11 and cap 12 and communicates with radial recesses 21 of base 11 and longitudinal recesses 22 of cap 12. As indicated in Figs. 2 and 3, fuse link 19 rests in one of the recesses 21 and passes up along the side of cap 15 12 in one of the recesses 22. It is to be noted that fuse link 19 does not fully occupy the space provided by these recesses. The end of cap 12 is spaced from shoulder 23 of base 11 by the portion of fuse link 19 which passes over the end 20 of cap 12 and engages projection 17 of base 11. This provides a communicating passage between recess 22 of cap 12 and the space between the side walls of the base 11 and cap 12. The insulating material of which the molded cap 12 is 25 made may be damaged by an arc persisting for a considerable length of time within the fuse upon its operation. To protect the side walls of cap 12 from direct contact with the arc and to insure a quick and certain extinction of the arc, a metal 30 sleeve 24 is provided substantially covering the inner wall of the extension 13 of cap 12. By the provision of this metal sleeve 24 the metallic vapor generated on volatilization of the fuse link 19 is condensed as it passes out of the fuse 35 through the recesses 21 and 22 provided for its escape. The metal sleeve 24 not only provides a surface of high heat conduction which will condense the metallic vapor but also prevents heat localization on the inner surface of extension 13 40 which may crack the extension. If extension 13 is injured then the arc may strike directly from the center terminal to the metal parts of the fuse support. An arc may then develop which will 45 do great damage to the fuse support and to the apparatus connected in the circuit. The condensation of this metallic vapor greatly reduces the amount of metal vapor in the arc path and so greatly reduces the length of time which the 50 arc will persist. It has been found that the provision of this metal sleeve not only results in the quick operation of the fuse but also assures the operation of the fuse even when a fuse of high 55 current rating is operated by an overload only

slightly in excess of the rating of the fuse. This metallic sleeve 24 may be made from a thin sheet of copper formed into a ring of substantially the diameter of the inner wall of extension 5 13. While copper is preferred, sleeve 24 may be made from any other metal.

From the foregoing, it may be seen that a plug fuse is provided with a metallic sleeve surrounding a portion of the fuse link which assures 10 a quick operation of the fuse without damage to the fuse and its support or the electrical devices which may be connected in the circuit by an undue prolongation of the fault. In addition, the metallic sleeve assures a completed 15 operation of the fuse even though the current may not greatly exceed the rating of the fuse.

What I claim as new and desire to secure by Letters Patent of the United States, is:

1. An electric fuse comprising a base of insulating material, a cap of insulating material, an extension from said cap passing over a portion of said base, communicating recesses to permit gases to escape between said extension and said base, a fuse link located within said extension, 25 and a metal sleeve covering the inner wall of

said extension whereby escaping gases may condense on said sleeve.

2. An electric fuse comprising a base of insulating material, a cap of insulating material having an extension passing over a portion of said base, communicating recesses to permit gases to escape between said extension and said base, a center contact secured to said base, a metal shell threaded over said base and cap, a fuse link connected to said center contact and said shell, and a metal sleeve covering the inner wall of the extension of said cap whereby escaping metallic vapors may condense on said sleeve.

3. An electric fuse comprising a base of insulating material, a cap of insulating material having an extension passing over a portion of said base, communicating recesses to permit gases to escape between said extension and said base, a center contact secured to said base, a metal shell threaded over said cap and base, a 20 fuse link connected to said center contact and said shell, and a metallic sleeve surrounding a portion of said fuse link whereby escaping metallic vapors may condense on said sleeve.

GEORGE R. BROWN. 25
